UNITED STATES PATENT OFFICE.

HERBERT GUETTLER, OF CHICAGO, ILLINOIS, ASSIGNEE, BY MESNE ASSIGNMENTS, TO
AMERICAN BARKING DRUM COMPANY, OF CHICAGO, ILLINOIS, A CORPORATION OF
ILLINOIS.

BARKING APPARATUS.

1,324,193.

Specification of Letters Patent. Patented Dec. 9, 1919.

Application filed October 19, 1916. Serial No. 126,556.

To all whom it may concern:

Be it known that I, HERBERT GUETTLER, a subject of the King of Norway, residing in the city of Chicago, county of Cook, and 5 State of Illinois, have invented certain new and useful Improvements in Barking Apparatus; and I do hereby declare the following to be a full, clear, and exact description of the invention, such as will enable others 10 skilled in the art to which it appertains to make and use the same.

This invention relates to bark removing machines of the type in which blocks of wood, from which the bark is to be removed, 15 are tumbled in a rotating drum. The wood may be barked dry or may be periodically immersed in a tank of water. The improvements permit continuous operation by continuously delivering the bark from the drum 20 into the tank and then removing it from the tank. The means for supporting the drum and the mechanism for driving it are of a character particularly suited to the heavy weight of the moving parts and the severe 25 service conditions, and are of such a character that the bark is not caught in the tank and cannot interfere with free rotation of the drum.

The invention also comprises means for 30 varying the charge of wood and the level of water in the drum, and the speed with which the wood passes through the drum when supplied continuously at one end and delivered in barked condition through the 35 other end. Means are also provided for effectively tumbling the blocks of wood in the drum and for keeping open the passages through which the bark is delivered into the tank, and there is a saving in water. When 40 working with wood which is easily barked, such for instance, as hemlock, the water may be drained from the drum and the barking carried on in the dry way.

Means are provided for returning to the 45 intake end of the drum any blocks of wood which have been discharged through the drum incompletely barked. The reclaimed bark can be used for fuel or for industrial purposes.

50 In the accompanying drawings—
Figuré 1 is a plan view of the apparatus;
Fig. 2 is a side elevation;
Fig. 3 is an end elevation showing the discharge end;

Fig. 4 is a transverse section on the line 55 4—4 of Fig. 2;

Fig. 5 is a sectional plan of a side guide roller and its supporting frame;

Fig. 6 is a detail of the sprocket wheel on 60 the drum by which it is rotated;

Fig. 7 is a fragmentary section of the drum illustrating the shape and position of the angle bars and one of the bar removing flights;

Fig. 8 is a similar view of a modified arrangement of the angle bars; and Fig. 9 shows a guard at the end of the drum.

The preferred embodiment of the invention shown in the drawings comprises a drum 1, cylindrical in shape, and open at 70 both ends. The drum is arranged for rotation in a tank 2 adapted to contain water and having a concave bottom substantially concentric throughout with the drum.

The cylindrical drum is composed of a 75 plurality of rings 3 to which are secured angle bars 4 having their flanges projecting inwardly and having their webs spaced apart, as shown in Figs. 7 and 8, to form long, narrow slots through which the bark 80 is delivered from the drum. By making the height H of the angle iron flanges less than half the distance D between adjacent flanges, the interior surface of the drum is sufficiently rough and irregular to insure 85 effective tumbling of the wood, and the blocks of wood do not become wedged and held between adjacent flanges and therefore do not close up the bark-discharging slots.

The drum 1 is supported by flexible end- 90 less elements, such as chains 5, which engage smooth rings 6 with which the drum is provided, and pass over smooth traction wheels 7 and 8 which are supported on a suitable frame 9. All of these wheels are 95 secured to independent axles, and the axles 10 of wheels 8 are journaled in suitable take-up bearings, each of which is pressed outward by a spring 11, the inner end of which is seated on a screw 12 which can be adjusted with a wrench to increase or decrease the tension on spring 11, thereby sliding the bearing with its axle 10 either inward or outward, and in this manner adjusting the tension on each individual supporting chain, 100 of which four may be used, as illustrated in the drawings. Not only can the slack of the chains thus be taken up independently and 105

the load evenly distributed on the several chains, but shocks and stresses incident to rotation of the drum are to a certain extent taken up by springs 11, thereby protecting 5 frame-work 9 and other associated parts.

As a means for rotating the drum, there is provided near its middle, an annular sprocket 13 (Fig. 6) bolted between the flanges of the two central drum rings 3, 10 which, for this purpose, are placed side by side with their flanges opposed. Engaging with the sprocket is a driving chain 14 which passes over a driving sprocket 15 secured to shaft 16, which is positioned above the upwardly moving side of the drum and is 15 driven in suitable manner as by a sprocket 17 and chain 18. This method of driving has many advantages. With drums of large diameter there is a tendency for them to 20 spring or yield under the heavy load of wood, and with this mode of driving they may be temporarily or even permanently deformed without serious inconvenience. The turning or rotating force, by its upward direction, tends to relieve somewhat 25 the tension on the four supporting chains, and by mounting shaft 16 substantially above the upwardly moving side of the drum, there is, in effect, a compensation for 30 the unequal distribution of wood within the drum while in action. The driving chain may be slack on the following side, thereby giving the drum freedom of movement when springs 11 are adjusted or yield during normal 35 operation of the apparatus. In order to prevent lateral swinging of the drum during rotation, it is provided adjacent its ends with guide rings 19 (Fig. 5) which are engaged by the flanged guide rollers 20, rotatably mounted upon the frame 9 at the 40 sides of the drum.

The blocks of wood from which the bark is to be detached are introduced into one end of the drum by means of a chute 21, and 45 after the bark has been removed, are delivered from the other end of the drum to a chute 22, preferably in the form of a grid, and down this they slide while being washed off with jets of water from a pipe 23. The 50 blocks are ultimately delivered to an endless conveyer 24 by which they may be transported to other parts of the mill. It is expedient to operate the drum under such conditions that not all of the wood discharged 55 over chute 22 shall be entirely barked, and to provide a conveyer 25 (Fig. 1) so that an operator standing at the discharge end of the drum can sort the wood and return the imperfectly barked pieces over conveyer 25 60 to the intake end of the drum, where they can again be fed through for further tumbling. The plurality of bark-discharging openings formed in the cylindrical surface of the drum between the angle bars 4, are 65 of such size that the pieces of detached bark

may pass freely therethrough and into the tank of water without permitting the escape of any of the blocks.

When the drum is to be used for barking slabs, edgings, or wood of like thickness, or 70 for barking mixtures of such thin materials with logs or blocks of ordinary dimensions as used in the paper making industry, I prefer to provide each longitudinal slot with a guard or baffle 3' (Figs. 7 and 8), preferably in the form of a series of flat strips having their ends turned up and riveted to the flanges of rings 3, the horizontal portions of these strips having a width substantially that of the slot and being spaced far enough 80 from the webs of angle bars 4 to afford a proper passage through which the bark can escape. Because of the tortuous character of this passage, slabs, edgings, or the like, can not work out to the outside of the drum 85 where, of course, such projecting pieces would interfere with free rotation and might seriously injure some part of the apparatus.

When working with ordinary round wood having dimensions of say two feet in length 90 and six to ten inches in diameter, these outer guards 3' are not necessary, and for convenience in illustration they have been omitted from Figs. 1 to 4, inclusive. It is to be understood, however, that this adjunct to the 95 drum can be applied or omitted as the needs of the user may dictate, and irrespective of the particular shape or grouping of the angle bars, or the like, within the drum, where-by the wood is tumbled.

Secured to the outer surface of the drum are a plurality of paddles or flights 26 in the form of combs or forks. As the drum rotates, these flights sweep through the water in tank 2 and remove therefrom the pieces 105 of bark which have passed into the tank of bark which have passed into the tank through the openings in the drum. This bark is discharged over the side wall 27 of the tank and received in compartment 28, which has a horizontal drain plate 29 and a 110 scraping conveyer 30 for transporting the bark toward one end of the drum for ultimate delivery to a drying apparatus, or the like, whereby the bark is rendered suitable for fuel or for industrial purposes. The 115 water draining off through plate 29 is collected in a drain 31 and conveyed away.

By supporting the drum upon the chains, as shown, the usual drum-supporting rollers are not required, and thus the bottom of the 120 tank is smooth throughout its entire extent and is free from any obstruction which might interfere with removal of the bark from the tank or with the free rotation of the drum.

Near the ends of the drum, the comb-shaped flights may be replaced by imperforate baffles 32 of spiral form secured to the outside of angle bars 4 and acting to propel inward toward the next adjacent section of 130

the drum such bark as might otherwise collect near the ends of the tank, or interfere with adequate clearance between the ends of the drum and the closures therefor.

- 5 As the drum rotates, the charge of wood is rotated until its upper surface assumes a certain critical angle, as indicated in Fig. 4, after which the blocks of wood tumble downward over one another and rub over 26. When thus operating in a dry way, there is advantage in spraying the blocks of wood with water prior to their exit from the drum, to wash off adhering dust and bits 70 of bark, and to this end spray pipe 23 may have openings along its side as well as along its bottom, and can be used for projecting water into the adjacent open end of the drum to wet down and wash off the blocks 75 of wood when they are approaching delivery from the drum.
- 10 one another in such a way that the bark becomes detached. The quantity of wood which can be treated, and consequently the angle of inclination which the surface of the charge assumes during the operation, 15 depends upon the quality and character of the wood. In order that the machine may be adapted to treat different quantities of wood, or different qualities of wood, adjustable means are provided adjacent the discharge end of the drum to vary the height 20 of the wood within the drum. As shown, the end posts 33 of frame 9 are adapted to support transversely extending planks 34 bolted thereto. When the planks are in 25 place, they register with the open discharge end of the drum and are in close proximity thereto. It will be understood that the level of the charge of wood in the drum depends upon the height of the barrier thus 30 built up by placing one plank above another.

The amount of water in the tank 2 should be varied in accordance with the quantity of wood in the drum in order that there may 35 be sufficient water in the tank to keep the wood thoroughly soaked down without, however, permitting it to float. By thus proportioning the amount of water to the quantity of wood being treated, the water 40 acts as a support for the wood and relieves, to a great extent, the weight which the chains 5 would otherwise be called upon to support. In order to vary the amount of water within the tank, the edge 27 thereof 45 comprises a plurality of removable sections placed one above another. These sections form a dam and provide ready means for varying the level of water within the tank.

With some kinds of wood, as, for instance, 50 hemlock, it is desirable at times to effect barking without periodically immersing the blocks of wood in water. By thus working in a dry way, the bark comes from the apparatus in dry conditions and needs no 55 treatment to render it suitable for use as a fuel. The preferred embodiment here disclosed is readily adaptable for dry barking, and to this end tank 2 is provided near its center with an outlet chamber 35 controlled 60 by a valve or gate 36 in a discharge pipe leading to a drain channel 37. Over this chamber 35 and conforming to the curved interior of the tank is a removable grid or grating 38 through which the bark will not 65 pass, and from which the bark will be

swept away by the moving flights or combs 26. When thus operating in a dry way, there is advantage in spraying the blocks of wood with water prior to their exit from the drum, to wash off adhering dust and bits 70 of bark, and to this end spray pipe 23 may have openings along its side as well as along its bottom, and can be used for projecting water into the adjacent open end of the drum to wet down and wash off the blocks 75 of wood when they are approaching delivery from the drum.

A considerable clearance must be allowed between the ends of the drum and the adjacent wooden barriers by which these ends 80 are partially closed, for otherwise the drum, due to warping or irregularities in its manufacture, might strike or chafe against the barrier. With a clearance of an inch and a half or two inches at each end of the 85 drum there is danger that small pieces of wood might work into the gap and there become wedged and either stop rotation of the drum or injure it, and to guard against this possibility, there is provided at each 90 end of the drum, a guard 39 attached to the adjacent barrier and overlapping the end of the drum sufficiently to close the clearance gap. In Fig. 9 this guard is in the form of an angle bar fastened to barrier 34 and shaped to conform to the curved lower half of the drum, up to about the level of guide rollers 20 (Fig. 3). A similar guard is used at the intake end of the 95 drum.

I claim:—

1. In a bark-removing machine, the combination of a drum adapted to receive blocks of wood at one end and discharge them at the other end, said drum having openings in its side; an endless driving chain encircling said drum; endless chains, separate from said driving chain, passing around said drum to yieldingly support it; a tank into which the lower portion of the drum 105 projects, adapted to contain water wherein the wood is immersed, the water entering the drum through said openings and acting to support the wood and thereby relieve the weight on said supporting chains; and means acting on said driving chain to rotate said drum in said supporting chains.

2. In a bark-removing machine, the combination of a drum adapted to receive blocks of wood at one end and discharge them at 120 the other end, said drum having openings in its side; an endless driving chain encircling said drum; endless flexible traveling elements, separate from said chain, passing around said drum to yieldingly support it; a tank into which the lower portion of the drum projects, adapted to contain water wherein the wood is immersed, the water entering the drum through said openings, 125 and acting to support the wood and thereby 130

relieve the weight on said supporting elements; and means acting on said chain to rotate said drum in said supporting elements, said means being located substantially above the upwardly-moving side of the drum so as to relieve the tension on said supporting elements.

3. In a bark-removing machine, the combination of a drum adapted to receive blocks 10 of wood at one end and discharge them at the other end; endless flexible traveling elements passing around said drum to yieldingly support it; an endless driving chain, separate from said supporting elements, 15 circling said drum; means acting on said chain to rotate said drum in said supporting elements; and spring means associated with said supporting elements for automatically taking up shocks incidental to the rotation 20 of the drum.

4. In a bark removing machine, the combination of a rotatable drum adapted to continuously receive blocks of wood at one end and to discharge them at the other end, 25 said drum having longitudinal bark discharging slots, endless chains supporting said drum, a pair of sheaves for each of said chains, one sheave of each pair having a spring-pressed take-up bearing, a driving 30 chain encircling said drum and means acting on said driving chain to rotate said drum in said supporting chains.

5. In a bark removing machine, the combination of a rotatable drum adapted to receive 35 blocks of wood at one end and to discharge them at the other end, said drum having bark discharging slots in its side, endless traveling elements encircling said drum to yieldingly support it, a driving 40 chain encircling said drum and passing over a driving sprocket, said sprocket being positioned substantially above the upwardly moving side of the drum, so as to relieve the tension on said supporting elements, and 45 means for rotating said sprocket to turn the drum and tumble the blocks of wood therein.

6. In a bark removing machine, the combination of a rotatable drum adapted to continuously receive blocks of wood at one 50 end and to discharge them at the other end, said drum having longitudinal bark discharging slots, endless elements supporting said drum, a pair of sheaves for each of said elements, one sheave of each pair having 55 spring-pressed take-up bearings, a sprocket encircling said drum, a driving chain for said sprocket, a driving sprocket positioned substantially above the upwardly moving side of said drum and over which said driving 60 chain is adjusted with enough slack on the following side to permit shifting of said take-up bearings, guiding means at the sides of said drum and means for turning said driving sprocket to rotate said drum in said 65 supporting elements.

7. In a bark removing machine, the combination of a rotatable drum adapted to continuously receive blocks of wood at one end and to discharge them at the other end, said drum having bark discharging slots in its side, a shallow tank adapted to contain water wherein the drum may rotate partly submerged to periodically submerge the wood under treatment, said tank being unobstructed from end to end and having a concave bottom which throughout is substantially concentric with the drum, endless chains supporting said drum, guide rings secured to the outer surface of the drum, rollers engaging the guide rings at the sides 75 of the drum, a driving chain encircling said drum, means acting on said chain to rotate said drum, and means carried by the drum for continuously lifting the bark over the edge of the tank as the drum rotates. 85

8. In a bark removing machine, the combination of a rotatable drum open from end to end and adapted to continuously receive blocks of wood from which the bark is to be removed by tumbling in the drum, said drum being provided with longitudinal bark releasing slots and a plurality of smooth, encircling rings, a shallow tank adapted to contain water wherein the drum may rotate partly submerged, said tank being unobstructed from end to end and having a concave bottom which throughout is substantially concentric with the drum, endless chains engaging said encircling rings and supporting the drum, smooth wheels by 90 which said chains are supported, a sprocket encircling said drum, a driving chain engaging said sprocket, means for actuating said driving chain to rotate said drum, and flights carried by the drum and adapted to 95 sweep through the tank for continuously removing the bark from the tank as the drum rotates. 100

9. In a bark removing machine, the combination of a rotatable drum open from end 110 to end and adapted to continuously receive blocks of wood from which the bark is to be removed by tumbling in the drum, said drum being provided with longitudinal bark-releasing slots and a plurality of encircling rings, endless chains supporting said drum at said rings, a plurality of sheaves for each chain, said sheaves being spaced apart a distance approximating the 115 diameter of the drum, an additional driving chain encircling said drum, means acting on said driving chain to rotate said drum in said supporting chains, and a tank adapted to contain water wherein the drum may 120 rotate partly submerged. 125

10. In a bark removing machine, the combination of a rotatable drum open from end to end and adapted to continuously receive blocks of wood from which the bark is to be

- removed by tumbling in the drum, said drum being provided with longitudinal bark-releasing slots and a plurality of smooth encircling rings, endless chains supporting said drum at said rings, a plurality of smooth sheaves for each chain, said sheaves being spaced apart a distance approximating the diameter of the drum, an additional driving chain encircling said drum, and means acting on said driving chain to rotate said drum in said supporting chains. 5
11. In a bark removing machine, the combination of a rotatable drum adapted to continuously receive blocks of wood at one end and to discharge them at the other end, said drum having longitudinal bark-discharging slots, endless chains supporting said drum, a pair of sheaves for each of said chains, 15 said sheaves being spaced apart a distance approximating the diameter of the drum, a spring-controlled takeup bearing for one of said sheaves and a chain drive for said drum. 20
12. In a bark removing machine, the combination of a rotatable drum adapted to receive blocks of wood at one end and to discharge them at the other end, said drum having bark-discharging slots in its side, endless traveling elements supported from spaced shafts forming a loop at least as large as the diameter of the drum, and a driving chain encircling said drum and passing over a driving sprocket, said 25 sprocket being positioned substantially above the upwardly moving side of the drum, substantially as described. 30
13. In a bark removing machine, the combination of a rotatable drum with open ends 40 adapted to continuously receive blocks of wood at one end and to continuously discharge them, after treatment, at the other end, a tank partly surrounding the drum and adapted to contain water wherein the wood is tumbled as the drum rotates, openings in the side of said drum for the passage of detached bark into the tank, and a spiral baffle on the outside of the drum near its end to clear the bark out of the end of the 45 tank. 50
14. In a bark removing machine, the combination of a rotatable drum open from end to end and adapted to continuously receive blocks of wood through one end and to continuously discharge them, after treatment, through the other end, a concave tank partly surrounding the drum and adapted to contain water wherein the wood is tumbled as 55
- the drum rotates, said drum having openings in its side for the passage of detached bark into the tank, flights on the outside of the drum for continuously removing the bark from the tank, and spiral baffles near the ends of the drum to clear the bark out of the ends of the tank. 60
15. In a barking apparatus, the combination of a rotatable drum with open ends adapted to continuously receive blocks of wood at one end and to continuously discharge them, after treatment, at the other 65 end, a tank partly surrounding the drum and adapted to contain water, when desired, said drum having openings in its side for the passage of detached bark into the tank, means for continuously removing the bark from the tank as the drum rotates, an inclined grid on which the wood discharged from the drum is delivered, means for washing it on the grid and means at the side of said drum and leading from near the discharge end thereof to the intake end thereof for returning pieces of wood for further treatment in the drum when desired. 70
16. In a barking apparatus, the combination of a rotatable drum with open ends 75 adapted to continuously receive blocks of wood at one end and to continuously discharge them, after treatment, at the other end, a tank partly surrounding the drum and adapted to contain water, when desired, said 80 drum having openings in its side for the passage of detached bark into the tank, means for continuously removing the bark from the tank as the drum rotates, a grid on which the wood discharged from the 85 drum is delivered, means for washing the wood on the grid and for delivering water to the wood within the drum. 90
17. A barking drum comprising rings connected by bars with slots between the bars 95 through which bark may escape, and baffles obstructing said slots to form tortuous passages for the discharge of bark, but through which wood under treatment will not pass. 100
18. A barking drum comprising rings connected by angle bars which have their flanges extending inward to tumble the wood to be barked, said angle bars being spaced apart to form longitudinal slots through which the detached bark may escape 110 from the drum, and additional bars over said slots to prevent protrusion therethrough of thin pieces of wood under treatment. 105

In testimon, whereof I affix my signature.

HERBERT GUETTLER.
